UNITED STATES PATENT OFFICE.

JOSEPH LAUHOFF, OF DETROIT, MICHIGAN.

MECHANICAL TELEPHONE.

SPECIFICATION forming part of Letters Patent No. 365,525, dated June 28, 1887.

Application filed August 21, 1886. Serial No. 211,547. (No model.)

To all whom it may concern:

Be it known that I, JOSEPH LAUHOFF, of Detroit, county of Wayne, State of Michigan, have invented a new and useful Improvement 5 in Mechanical Telephones; and I declare the following to be a full, clear, and exact description of the same, such as will enable others skilled in the art to which it pertains to make and use it, reference being had to the accompanying drawings, which form a part of this specification.

My invention relates to certain new and useful improvements in "mechanical telephones," my object being to provide a telephone of this 15 class which shall be simple in construction and efficient in its operation.

My invention therefore consists in the combinations of devices and appliances herein-after specified, and more particularly pointed 20 out in the claims.

I carry out my invention as follows:

In the drawings, Figure 1 is a vertical section of a device embodying my invention. Fig. 2 is a front view with the front diaphragm removed.

A represents any suitable inclosing case, constructed with a front orifice, *a*, of desired diameter, and provided at its rear with an orifice, *a'*, through which the line-wire or steel 30 tape B is extended.

C is a tubular shell, supported within the case A in any suitable manner, as by means of a bracket, D. To form the engagement of the shell with the bracket, a collar, E, may be 35 employed, the collar being engaged to the shell and to the bracket.

F represents a rear diaphragm engaged upon the shell, provided with an orifice at *e*, through which the line-wire passes.

40 F' represents the front diaphragm removably engaged upon the forward part of the shell. b is the button by which the line-wire is connected with this front diaphragm. The rear diaphragm preferably has a fixed engagement in the shell. The front diaphragm is supported upon a ring, G, said ring constructed so as to form a sharp contact-edge, on which the diaphragm is located.

g g', &c., represent supports for the ring. 45 These supports are engaged at their base with an annular bed-piece, G'.

H is a rim located on the inside of the shell, to form a rest for said bed-piece.

It will be observed that the shell, the rear

diaphragm, and the front diaphragm form a 55 sounding-chamber partially divided by the bed-piece G', said bed-piece having a removable engagement upon the rest H, so that said bed-piece and front diaphragm engaged upon the edge of the ring G are left free to vibrate. 60

What I claim is—

1. In a telephone, the combination, with the removable bed-piece G', of a ring, G, engaged therewith by intervening supports, substantially as described.

2. In a telephone, the combination, with a removable bed-piece, G', of a ring engaged therewith by intervening supports, and a removable diaphragm located upon said ring, substantially as described.

3. In a telephone, a sounding-chamber provided with front and rear diaphragms, said chamber divided by a removable bed-piece, G', the front diaphragm removably engaged upon a ring support on said bed-piece, substantially as described.

4. In a telephone, the combination, with a shell, of front and rear diaphragms connected therewith, and a removable bed-piece supported within said shell, the front diaphragm removably engaged upon a ring supported upon said bed-piece, substantially as described.

5. A mechanical telephone constructed of a case having in combination therewith an inner shell provided with front and rear diaphragms inclosing a sounding-chamber, and a movable bed-piece located within said shell, the front diaphragm removably engaged upon a ring supported on said bed-piece and provided with a line-wire or steel tape, substantially as described.

6. In a telephone, a sounding chamber provided with front and rear diaphragms, and a movable bed-piece located within said sounding-chamber, provided with a ring supported 95 thereon, the front diaphragm removably engaged upon said ring and held in contact therewith by a line-wire or steel tape, the construction being such that said front diaphragm and bed-piece are free to vibrate, substantially 100 as and in the manner described.

In testimony whereof I sign this specification in the presence of two witnesses.

JOSEPH LAUHOFF.

Witnesses:

N. S. WRIGHT,
M. O'DOGHERTY.
